Inventor
Philip E. Edelman

UNITED STATES PATENT OFFICE

98,664

DESIGN FOR AN ELECTRICAL HUMIDIFIER

Philip E. Edelman, Chicago, Ill.

Application November 6, 1935, Serial No. 59,403

Term of patent 3½ years

To all whom it may concern:

Be it known that I, Philip E. Edelman, a citizen of the United States, residing at Chicago, Illinois, have invented a new, original, and ornamental Design for an Electrical Humidifier, of which the following is a specification, reference being had to the accompanying drawing, forming part thereof.

Figure 1 is a side elevational view of the electrical humidifier, showing my design; and
Figure 2 is a perspective view thereof.

I claim:

The ornamental design for an electrical humidifier, as shown.

PHILIP E. EDELMAN.
